KNOB WITH DEMOUNTABLE CORE LOCK

Henry G. Voight, New Haven, Conn., assignor to
 Sargent & Company, New Haven, Conn., a
 corporation of Connecticut

Application August 15, 1935, Serial No. 36,253

14 Claims. (Cl. 70—91)

This invention relates to locks, and more particularly to a door lock wherein the lock core may be removably and releasably retained within the lock case. The lock case in the embodiment of my invention shown in the drawings is the usual door knob which, as is often the custom in connection with door locks at the present time, is adapted to contain the usual pin tumbler locking mechanism by which the lock or latch bolt may be actuated.

In connection with door locks, and particularly those used upon hotel or office doors, a great deal of inconvenience arises due to the fact that keys are lost or carried away and thus remain in or come into the hands of unauthorized persons. Ordinarily it is a matter of considerable trouble and expense to remove the lock mechanism and either effect a key change therein or replace it with another lock.

The present invention has for one of its objects the provision of a locking mechanism having a housing provided with means for releasably engaging the case within which the locking mechanism is mounted, whereby this mechanism is retained in place during ordinary operations of the lock, but which may be readily removed by a person with the proper key.

Another object of my invention is to provide a knob or lock casing with a removable locking mechanism which may be removed by an authorized person who understands the mechanism by the same key as is employed to operate the lock or latch bolt.

Another object of the invention is the provision of a case for containing a locking mechanism, and means for releasably retaining the locking mechanism within the case of such a character that the retaining means may be readily disengaged without the use of any tools other than a key that fits the lock.

A still further object of the invention is the provision of a lock case designed to contain a pin tumbler lock core, and the provision of inter-engaging means on the case and core to retain the latter in the case, such that while the retaining means is not actuated by the key, it will be restrained from movement to releasing position until the key barrel is moved to a predetermined position.

To these and other ends the invention consists in the novel features and combinations of parts to be hereinafter described and claimed.

In the drawings:

Fig. 1 is an elevational view of a door lock embodying my invention;

Fig. 2 is an edge view of the lock as applied to the door;

Fig. 3 is a section through the knob and locking mechanism on line 3—3 of Fig. 2;

Fig. 4 is a transverse sectional view on line 4—4 of Fig. 3;

Fig. 5 is a sectional view on line 5—5 of Fig. 3;

Fig. 6 is a sectional view similar to Fig. 5 but showing the key barrel in a different angular position;

Fig. 7 is a sectional view on line 7—7 of Fig. 3;

Fig. 8 is a longitudinal sectional view through the door knob and lock taken at right angles to that shown in Fig. 3, and somewhat enlarged;

Fig. 9 is an enlarged sectional view of the door knob similar to that shown in Fig. 3, with the lock core removed;

Fig. 10 is a face view of the knob shown in Fig. 9;

Fig. 11 is a sectional view of the lock core removed from the knob, the key barrel being shown in elevation; and

Fig. 12 is an end view of the lock core shown in Fig. 11.

In order to illustrate a preferred embodiment of my invention I have shown a portion of a door at 10, having a lock or latch mechanism generally designated by the numeral 11 secured thereto, the bolt thereof being shown at 12 in Fig. 2. The lock is provided with the usual outside knob 13 and inside knob 14, the former of which may, as is more or less usual in locks of the present character, be rigidly secured in place so that the bolt 12 will be operated entirely through the pin tumbler lock mechanism, as will be presently described.

As shown in Fig. 3, the knob 13 is hollow, as is likewise the shank 15, which may be provided with an annular internal shoulder 16.

Within the knob is removably mounted the lock unit or core shown in Figs. 11 and 12. This unit is of the usual type of pin tumbler locks, and comprises a housing having a cylindrical portion 17 within which is rotatably mounted the key barrel 18, and which is provided with a so-called extension 19 within which the drivers of the pin tumblers are mounted according to the usual practice. A face plate 20 is secured to the lock housing, and this face plate is designed to fit snugly within an opening 21 in the face of the knob when the core or locking unit is inserted therein.

The key barrel 18 may be retained within the housing 17 by means of an enlargement 22 on the forward end of the barrel, and a collar 23

secured on the reduced rear end 24 of the key barrel and abutting the cylindrical portion 17 of the housing. The collar 23 may be secured in place by means of a set screw 25, shown in Figs. 5 and 6, and is provided with a non-circular opening 26 to receive the operating spindle 27 of the lock. It will be understood that this spindle is slidably received in the opening 26 so that the core when released, comprising the lock housing and key barrel, may be removed from the knob.

As shown in Fig. 8, the inner face of the knob cavity may be recessed as at 28 and 29, and ribs 30 and 31 on the lock housing 17 may enter these recesses to retain the lock housing against rotation within the knob. The rib 31 is, as will be seen from Fig. 8, a continuation of the pin tumbler extension 19.

In order to retain the lock housing within the knob, which in this instance serves as the lock case, I have provided interengaging means between the housing and case which will be automatically engaged when the housing is inserted into the case by a longitudinal thrust, but which may be readily released by anyone having a key which will fit the pin tumbler lock without the necessity of use of any other tools. To effect this result I secure to a side of the housing, as shown more especially in Figs. 3, 8, and 11, a leaf spring or strap of resilient material 32, one end of which is rigidly secured to the lock housing by means of the screw 33. The free end of the spring 32 carries a projecting pin 34 which is designed to be received in an opening 35 in the wall of the knob shank. The lock housing is recessed or grooved as shown at 32^a to permit the free end of the spring to be moved toward the axis of the housing or away from the knob shank to release the pin 34 from the opening 40 of the shank when this is desired.

In order that this release may be effected, a driver 36 is movably mounted within a recess 37 in the knob shank, this driver having reduced ends and an enlarged middle portion whereby the outer end may be accessible for depression by the thumb nail of the operator, and whereby the inner end may enter the opening 35 in the knob shank to engage the pin 34 and drive this pin inwardly out of engagement with the opening 35.

The knob shank is provided externally with a groove or recess 40 within which the driver 36 lies, and the walls of this groove may be closed together slightly over the enlarged central portion 45 of the driver 36, as shown at 41 in Fig. 9, to prevent this driver from dropping out of its seat in the knob. It will be seen, therefore, that the driver will always be retained in position, and will always be accessible for engagement by the thumb nail of the operator to retract the pin 34 and move it out of the opening 35.

As the lock housing 17 is held rigidly within the knob, and as the spring member 32 to which the pin 34 is attached is secured to this housing, it will be understood that the latter lies at all times within the opening 35 when the lock housing is within the knob. It is necessary, therefore, to provide some means to prevent the retraction of the pin 34 by an unauthorized person, who otherwise could merely depress the driver 36 with his thumb nail and thus withdraw the lock housing from the case or knob. This result is effected in the following manner. It will be seen that the shoulder 42 on the collar 23 stands opposite the pin 34, and that this shoulder is

substantially equal in diameter to that of the cylindrical housing 17 of the key barrel. While, therefore, the free end of the spring 32 might otherwise be depressed within the recess or groove 32^a, it is prevented from being so moved by the shoulder 42, except in one position of the key barrel to which the collar is secured by the screw 25. As shown in Figs. 3, 5, 6, and 8, this shoulder is provided with a recess 43 at one portion thereof, the recess being of sufficient width to receive the spring member 32. When the key barrel has been turned to such a position that this recess lies below the spring, the latter will no longer be restrained from being moved inwardly, and it may be so moved by the driver 36 and the pin 34 thereby released from the opening 35.

It will be understood that in the usual locked position of the lock, that is, the position wherein the pin tumblers in the key barrel 18 are opposite the drivers in the extension 19 so that the key 20 may be removed, the slot or groove 43 occupies a position remote from that of the spring 32, so that this spring cannot be depressed and the lock core withdrawn. Moreover, it will usually be found advisable to provide for the movement 25 of the key in one direction, say to the right, as shown in Fig. 1, to retract the latch mechanism, and to provide for movement of the key in the opposite direction, that is, to the left, as shown in Fig. 1, to bring the key barrel to a position 30 in which the lock housing may be removed from the knob.

The key barrel may be limited in its rotation by the provision of a slot 45 therein, as shown in Fig. 11, and the end of the screw 33 may project 35 within this slot. The slot may, if desired, be of such a length and be so disposed that when the key is moved to the left from the position shown in Fig. 1 the motion will be checked at the position in which the groove 43 lies below the end 40 of the spring 32, so that the position of the key barrel in which removal of the lock core is permitted is readily defined.

It will be observed that the pin 34 and driver 36 have an operation similar to that of the usual 45 pin tumblers, in that one is a retaining pin and the other a driver, and a "break" is arranged between the two at a point on the inner surface of the knob. The portion of the knob shank within which is disposed the shoulder 42 of the collar 50 23 and the free end of the spring 32, may be provided with a beveled recess 46, as shown in Fig. 9, to automatically depress the pin 34 when the lock housing is inserted into the knob. When the pin 34 arrives at a position opposite the opening 35, 55 it will, of course, automatically spring into this opening.

The operation of my device is as follows: When it is desired to insert the lock core within the knob, a key is inserted in the key plug and the latter turned to the left to bring the groove 43 opposite the pin 34 on the spring 32 secured to the lock housing. The lock core, consisting of the key barrel, the lock housing 17 and associated parts, and the face plate 20, is then inserted 65 into the knob in the position at which the ribs 30 and 31 align with the grooves or recesses 28 and 29. When the lock core is pushed into place the spring 32 will be cammed inwardly by the bottom of the groove 46, and will spring outwardly 70 when it arrives opposite the opening 35, so that the pin 34 will be engaged with the wall of this opening and retain the lock core in place. It will be observed that the key barrel may now be rotated in its usual lock or latch operating move- 75

ments without having any effect upon the inter-engaging retaining means holding the lock core in place, as the spring 32 is secured to the lock housing and not to the key barrel.

- 5 When it is desired to remove the lock core from the knob, the key is turned (to the left from the position shown in Fig. 1) to bring the groove 43 below the end of the pin 34. The operator may then insert his thumb nail in the groove 40 where 10 he can engage the end of the driver 36 and depress this driver to a sufficient extent to bring the break between its inner end and the outer end of the pin 34 opposite the inner surface of the knob shank. The core may then be removed by a longitudinal pull upon the key.

15 While I have shown and described a preferred embodiment of my invention, it will be understood that it is not to be limited to all of the details shown, but is capable of modification and 20 variation within the spirit of the invention and within the scope of the appended claims.

What I claim is:

1. In a lock mechanism, a door knob, a lock core detachably mounted in the knob and withdrawable through the face of the knob, said core comprising a housing and a key barrel rotatably carried by the housing, means carried by the housing to automatically engage the knob when the core is inserted therein to releasably retain 30 the core within the knob, and means movably carried by the knob for effecting release of said member to permit withdrawal of the core from the knob.

2. In a mechanism of the class described, a door knob having a shank, a core insertable into and withdrawable from the face of the knob, said core comprising a housing and a key barrel rotatable therein, means for securing said housing against rotation relatively to the knob when in 35 position therein, means carried by said housing to releasably engage the knob shank and retain the core in the knob, and means movably carried by the knob shank for effecting release of said engaging means to permit withdrawal of the core 45 from the knob.

3. In a mechanism of the class described, a lock case, a core insertable into and withdrawable from the case, said core comprising a housing and a key barrel rotatable therein, means for securing said housing against rotation relatively to the case when in position therein, means carried by said housing to releasably engage the case and retain the core in the case, and means movably mounted in a wall of the case to effect disengagement of 50 said engaging means therefrom.

4. A lock case and a lock core insertable therein and withdrawable therefrom, said core comprising a housing and a key barrel rotatably mounted in the housing, said case being provided 55 with an abutment, and a spring-pressed member carried by the housing adapted to automatically engage said abutment when the core is inserted in the case and retain it therein, and means carried by the case to depress said member against the action of its spring and release the core for withdrawal.

5. A lock case and a core removably mounted in the case and comprising a housing and a key barrel rotatably mounted in the housing, a two-part spring-pressed retaining member engaging said case and housing to retain the core within the case, and said member extending to the exterior of the case to be accessible for movement against 70 the action of its spring to disengage the inner

part thereof from the case and permit withdrawal of the core.

6. A lock case and a core removably mounted in the case and comprising a housing and a key barrel rotatably mounted in the housing, a two-part spring-pressed retaining member engaging said case and housing to retain the core within the case, said member being movable against the action of its spring to disengage the inner part thereof from the case and permit withdrawal of 10 the core, and the outer part of said member being movably mounted in the wall of the case.

7. A lock case and a core removably mounted in the case and comprising a housing and a key barrel rotatably mounted in the housing, a two-part spring-pressed retaining member engaging said case and housing to retain the core within the case, said member being movable against the action of its spring to disengage the inner part thereof from the case and permit withdrawal of 15 the core, and the outer part of said member being movably mounted in the wall of the case and extending to the exterior thereof to be accessible for manipulation.

8. A lock case having a core insertable therein 20 and withdrawable therefrom, said core including a housing non-rotatably mounted in the case when in position therein, and a key barrel rotatably mounted in the housing, a spring-pressed member carried by the housing and engageable 25 in an opening in a wall of the case to secure the core therein, and a driver movably mounted in the opening in the housing and adapted to be depressed to move said pin to disengaging position 30 to release the core for withdrawal from the case.

9. A lock case having a core insertable therein 35 and withdrawable therefrom, said core including a housing non-rotatably mounted in the case when in position therein, and a key barrel rotatably mounted in the housing, a spring-pressed 40 member carried by the housing and engageable in an opening in a wall of the case to secure the core therein, and a driver movably mounted in the opening in the housing and adapted to be depressed to move said pin to disengaging position 45 to release the core for withdrawal from the case, said driver being secured against removal from the wall of the case.

10. A lock case having a core insertable therein 50 and withdrawable therefrom, said core including a housing non-rotatably mounted in the case when in position therein, and a key barrel rotatably mounted in the housing, a spring-pressed member carried by the housing and engageable 55 in an opening in a wall of the case to secure the core therein, and a driver movably mounted in the opening in the housing and adapted to be depressed to move said pin to disengaging position to release the core for withdrawal from the case, said pin being restrained against movement to 60 disengaging position until said key barrel has been moved to a predetermined position.

11. A lock case and a core insertable into and withdrawable from the case and comprising a 65 housing and a rotatable key barrel, a spring-pressed member carried by the housing and releasably engaged with the case to retain the core therein, said member being depressible away from the case to disengaging position against the action of its spring, means rotatable with the key barrel for normally preventing a depressing movement of said engaging means, said preventing means being movable to inoperable position by rotation of the key barrel to permit movement 70 of the retaining member to disengaging position 75

whereby the core may be withdrawn from the case, and depressible means carried by a wall of the case to contact and depress said member.

12. A lock comprising a case and a core removably mounted therein, said core comprising a housing and a key barrel rotatably mounted in the housing, a spring member secured at one end to the housing and being free for movement at its other end, a pin upon the free end of said member 10 adapted to engage a part of the case to retain the core therein, and the free end of said spring being normally held against movement away from the case by a part of the key barrel, and said part having a recess therein to permit movement of the free end of the spring when the key barrel has been rotated to a predetermined position to release the pin from engagement with the case.

13. In a lock, the combination of a lock case, a 20 lock housing non-rotatably but detachably connected to the case, a key plug rotatably mounted

within said housing, and means carried by the housing and non-rotatably secured thereto to releasably engage the case and retain the housing therein, said means being operable from the exterior of the case for movement to disengaging position only in a predetermined position of said key barrel and a depressible member carried by the case to engage and operate said means. 5

14. In a lock, the combination of a lock case, a lock housing non-rotatably but detachably connected to the case, a key plug rotatably mounted within said housing, means carried by the housing and non-rotatably secured thereto to releasably engage the case and retain the housing therein, said means being movable to disengaging position only in a predetermined position of said key plug, and a member movably mounted in the case and extending to the exterior thereof for moving said means to disengaging position. 10 15

HENRY G. VOIGHT.
